RENNERT, OF BALTIMORE, MARYLAND.

COMBINATION PULLING-JACK.

1,064,400.

Specification of Letters Patent. Patented June 10, 1913.

Application filed July 6, 1912. Serial No. 703,033.

To all whom it may concern:

Be it known that I, GUY E. TIMMINS, a citizen of the United States, and a resident of Baltimore city, Maryland, have invented 5 certain new and useful Improvements in Combination Pulling-Jacks, of which the following is a specification.

This invention relates to a combination tool for quickly and easily removing pulleys, 10 gears, wheels and the like from their shafts or hubs.

The principal object of the invention is to provide a combination device which is simple and efficient and which is adjustable 15 to various sizes of pulleys, wheels, etc.

Other objects and the novel features of the invention will be apparent from the following description taken in connection with the accompanying drawings, in which:

20 Figure 1 is a side elevation of the device, the jaws being shown in one of a number of adjusted positions; Fig. 2 is a central vertical sectional view of the device, the jaws being adjusted to a different position; Fig. 25 3 is a plan view of the bar member, the jaws being removed; and Fig. 4 is a perspective view of one of the adjustable jaws or hooks.

Referring to the drawings, 10 designates 30 a bar rectangular in cross section and made of steel or other suitable material. About centrally intermediate the ends of the bar 10, and formed integrally with the sides thereof, there are curved, horizontally extending projecting portions 11 and 12 for 35 reinforcing the bar at or near its central section. The bar 10 forms oppositely extending arms for the central, threaded screw supporting section.

Depending from the under side of the 40 bar in line with the reinforced section there is an integral extension. A wrench head 13 is formed on the integral extension adjacent the bar 10. The outer end of the extension is bored out and forms a combined male 45 and female cap or nipple 14, which has external threads 15 and internal threads 16.

A threaded opening 17 extends centrally 50 through the reinforced section of the bar and the integral extension thereon. A threaded jack screw 18 provided with the wrench head 19 is fitted into the threaded opening 17 to operate therein. An opening 20 extending through the head 19 of the jack screw serves to receive a lever arm 21 55 by means of which the screw may be turned.

One of the depending removable and adjustable jaws 22, 22 is shown in detail in Fig. 4. Each jaw comprises a prismatic head section 23 which has four rectangular faces meeting at right angles. In each of the vertical faces of said head section there is a rectangular opening 25, the dimensions of which are slightly greater than the cross sectional dimensions of the bar. In each of the vertical faces of said head section there is a rectangular opening 25, the dimensions of which are slightly greater than the cross sectional dimensions of the bar. The openings in the faces intersect and extend through the head. They connect with the openings in the faces opposite so as to receive the end of the bar 10 and allow the latter to pass through the head 23, thereby permitting adjustment of each jaw longitudinally of the bar.

There is a finger piece 27, the shank 28 of which is threaded and passes through a threaded opening 29 in the top of the head 23 to engage against the cross bar 10 and hold the jaw 22 against movement when adjusted to suit.

The shank 28 is connected integrally with the head 23 of the jaw 22, and the end 31 of said shank is bent around to form a hook 32.

By reason of the four openings in each head of the jaws 22 the cooperating hooks 32, 32 may be reversed and adjusted in any one of a number of positions to accommodate the object upon which the jack is to operate. For instance, the hooks may be disposed as in Fig. 1 in the plane of the bar 10, facing each other, so as to engage the flange of a pulley or gear from the outer side, or they may be disposed as in Fig. 2, in the same plane adjusted to face in opposite directions to engage the flange at the inner side. They may also be adjusted to a position at right angles to the bar from either side, and it will be apparent that a number of other combinations of adjustments are possible.

To operate the device the jack screw 18 is retracted sufficiently, and the jaws 22, 22 are adjusted to the object, such as a pulley, which it is desired to remove from its support, such as a shaft. The screw being turned to move forward, the tip end will engage the end of the shaft causing a pulling pressure and will force the bar and jaws connected thereto outwardly and carry with them the pulley connected thereto.

The cap 14, having the male and female threads, which is located on the bar in line with the jack screw, may be used in con-

junction with or in place of the hooked jaws on the hub of a wheel which is threaded at its end to receive a cap, a construction which is common in automobiles. The arrangement may also be applied to assist in the removal of valves in engines of the internal combustion type especially. The member 14 is screwed onto the threaded portion and the forcing screw when turned will cause 10 a pressure in line with both elements of the tool. When it is desired to use the nipple alone the hooked members are removed from the bar.

The device combines in one a convenient 15 and reliable tool readily adjustable to numerous objects and dispenses with the necessity of having a number of tools.

Various modifications may be made without departing from the spirit of the invention, and it is therefore to be understood 20 that the invention is not limited to the exact details as shown and described except as required by the appended claims.

Having thus described the invention, what 25 is claimed is:

1. In a tool for removing pulleys, gears and the like from their supporting shafts, the combination of a forcing screw adapted to be set in line with the shaft and to engage 30 the latter at its end, a bar for operatively supporting the screw, independently adjustable members supported on the bar at oppo-

site sides of the screw and having lateral projections at their free ends adapted to engage the pulley, gear or the like, said members having openings therethrough disposed in intersecting planes, said openings being adapted to receive the bar and arranged so that the said lateral projections may be positioned to be parallel or at an angle to said 40 bar.

2. In a tool of the class described, the combination of a jack screw adapted to be located in line with an element and to engage the latter, a member for operatively 45 supporting the screw, and an internally and externally threaded nipple centrally in line with the screw and integrally connected to said member.

3. In a tool of the class described, the 50 combination of a screw, means for operatively supporting the screw and having oppositely directed arms, adjustable members slidable on the arms and having projections thereon for engaging an element, each member having an opening therethrough to receive the bar, and means for securing the members in their adjusted positions.

In testimony whereof I affix my signature in presence of two witnesses.

GUY E. TIMMINS.
